(57) **CLAIM**

The ornamental design for a Christmas cap, as shown and described.

DESCRIPTION

FIG. 1 is a front perspective view of the Christmas cap showing my new design;

FIG. 2 is a front elevation view thereof;

FIG. 3 is a rear elevation view thereof;

FIG. 4 is a left side elevation view thereof;

FIG. 5 is right side elevation view thereof;

FIG. 6 is a top plan view thereof; and,

FIG. 7 is a bottom plan view thereof.

The dash-dot-dash broken lines define the bounds of the claim and form no part of the claimed design.

The stippling in the drawings indicate a contrasting appearance with the adjacent lined areas of the Christmas cap.
